UNITED STATES PATENT OFFICE.

ARTHUR A. MERRITT, OF WORCESTER, MASSACHUSETTS, ASSIGNOR TO WILLCOX & GIBBS SEWING MACHINE CO., OF NEW YORK, N. Y., A CORPORATION OF NEW YORK.

SEWING-MACHINE PRESSER-FOOT.

1,388,360.

Specification of Letters Patent. Patented Aug. 23, 1921.

Application filed October 24, 1917. Serial No. 198,249.

To all whom it may concern:

Be it known that I, ARTHUR A. MERRITT, a citizen of the United States of America, and a resident of Worcester, Massachusetts, have invented a new and useful Improvement in Sewing-Machine Presser-Foots, which invention is fully set forth in the following specification.

The present invention relates to improvements in presser feet for sewing machines. Although designed especially for use with what is known commercially as the Willcox & Gibbs Sewing Machine Co.'s "flatlock machines"—shown for example in patents to 15 Stockton Borton 1,041,574, and to A. A. Merritt 1,041,652, both dated Oct. 15, 1912, and producing the seam of Borton Patent 883,614, dated March 31, 1908—this invention is not restricted to use with any particular type or make of sewing machine.

In the presser foot of this invention, the work-contacting surface is divided longitudinally of the seam into two separately movable sections or members, for engagement with the work along opposite sides of the medial line of the seam respectively. 25 One of said members is yieldingly movable, under spring control, relatively to the other, to permit its work-contacting surface to assume a position either above or below the corresponding surface of the other member. As so generally constructed, the presser foot affords approximately equal feed control and uniform advance of the work at both 30 sides of a seam when a certain thickness of fabric (either one or more layers) at one edge is to be joined to a different thickness (either one or more layers) at the other edge of the seam. An ordinary presser-foot operating under such conditions gives an uneven feed control resulting in a drawn or distorted seam. One of said foot members is further adapted to rock or tilt in the direction of the length of the seam and therefore 35 maintain the even feed control in passing over variations of thickness; for example, where it is necessary to cross a previously made seam.

Another object attained by the invention 50 is the provision of readily removable work-contacting parts of the foot, cheaply replaceable when defective from wear, and also readily changeable for similar parts of other thickness to change the elevation of 55 cut by the trimmer blades. Such change in

the elevation of cut becomes desirable, according to the character of the goods, to vary the width of upstanding edges left to be flattened into the seam and bound and secured together by the stitching. For example, with loosely woven knit goods, the cut should be relatively higher than with tightly woven knit goods. The work-contacting parts may also be changed to vary the width of notch in which the upturned edges of the fabric advance to the trimmer blades—a wider notch for thicker fabric.

The aforesaid and other novel features of invention will be more fully explained with reference to the accompanying drawings 70 illustrating what is now believed to be the preferred embodiment of the invention as applied to a machine of the character of the aforesaid flatlock machines. In said drawings—

Figure 1 is a front perspective view;

Fig. 2 is a rear perspective looking in the opposite direction from Fig. 1, with the presser foot stripped of attachments illustrated in said Fig. 1, and including a showing of the presser-foot bar;

Fig. 3 is a detailed perspective showing particularly the bifurcated lower portion of the main body of the foot;

Fig. 4 is a plan view omitting some of the attachments shown in Fig. 1, but including fixed presser-foot guide members not shown in said Fig. 1;

Figs. 5 and 6 are details of the guide members shown in Fig. 4;

Fig. 7 is a detail of a trimming-deflector or guard for guiding trimmings to one side and away from the needles;

Fig. 8 is a vertical section on line 8—8 of Fig. 4;

Fig. 9 is a vertical section on line 9—9 of Fig. 4;

Fig. 10 shows in detached relationship two of the work-contacting shoes or bottoms of the presser foot and the parts for attaching 100 the same to the main body of the foot;

Fig. 11 shows a detached foot bottom of greater thickness than that illustrated in Fig. 9;

Fig. 12 is a vertical central section on line 105 12—12 of Fig. 13;

Fig. 13 is a bottom view showing only the work-contacting parts of the presser-foot with a narrow notch between the toes, for use with relatively thin fabric;

75

90

95

110

Fig. 14 is a similar view illustrating the substitution of parts formed to constitute a wider notch for relatively thicker fabric and a chaining-foot with a correspondingly 5 larger notch;

Fig. 15 is a detail perspective view of the chaining-foot turned upside down;

Fig. 16 is a detail section on line 16-16 of Fig. 4;

10 Fig. 17 is a front end view of part of the presser foot, with a work-plate, feed member, and part of a work-arm supporting said work-plate, all shown in section, and with two thicknesses of fabric under one side of 15 the presser foot to be joined to a single thickness of fabric under the other side of the foot;

Fig. 18 is a detail view with a work-plate in section, particularly illustrative of the 20 tilting action of the movable member of the presser-foot;

Fig. 19 is a side elevation of a presser foot with a locking device of different form from that shown in the other figures for securing the movable section of the foot 25 against movement independent of the fixed section thereof; and

Fig. 20 is a detail perspective view of the locking element of Fig. 19.

30 In a number of particulars the presser foot herein illustrated is substantially that of Figs. 46 and 47 of the aforesaid Merritt Patent No. 1,041,652. 30 is the main body of the foot having a split hub 31 and a contracting screw for securely clamping the foot to the lower reduced end of the foot-bar 32 (Fig. 2). Bar 32 is vertically movable in the head of the machine, a portion of the wall of which is shown at 33 in Fig. 2. The 35 usual spring 34, the tension of which may be adjusted by a nut or plug 35, yieldingly presses the foot against the work while permitting vertical vibrations thereof in response to upward movements of the feed. A 40 cross-thread carrier 36, a cross-thread hook 37, driving connections therefor, and the mounting of these parts on the foot-body 30, are substantially the same as in the aforesaid Figs. 46 and 47 of Merritt Patent 45 1,041,652. Thus, said hook 37 is removably secured by a set-screw to the lower end of an upright shaft 38, Fig. 1, rotatable in an extension 39 of the foot-body 30. A rock-lever 40 (Fig. 1) secured to the upper end of shaft 38 has a long arm and a short arm, the latter connected by link 41 to a driving part not shown in the drawings hereof. The long arm of 40 extends in a curve to a pivotal connection with one end of a link 42, the 45 other end of said link being in turn pivotally connected to crank-arm 43 at the upper end of a shaft 44 journaled in an upright opening 45 (Figs. 2 and 4) in foot-body 30. Cross-thread carrier 36 is detachably secured 50 to the lower end of shaft 44. The cross-

thread hook 37 and thread-carrier 36 operate in the manner set forth in the patents aforesaid.

In its vertical movements, when lifted to introduce work and when lifted by upward 70 movements of the feed members, the presser foot is guided and held against sidewise movement by the following means shown in Figs. 4, 5 and 6:—A bracket-arm 46, adapted to be secured to the underside of the head of the machine (not shown) has a flattened bearing surface 47 working against a similar surface 48 at one side of the foot-body 30. A plate 49, constituting a detachable section of the front cover of the head of the machine, has a depending extension carrying bearing-block 50 engaging a flattened upright bearing surface 51 at the other side of the foot-body 30.

The horizontally disposed flattened portion of the foot-body 30, which extends forward of what constitutes the shank of the foot, is bifurcated to form two toes or branches 55, 56 (Fig. 3) separated by a notch in which the upturned edges of the fabric 90 to be trimmed advance and are trimmed by the trimmer-blades. Fixed trimmer-blade 57 is secured to the underside of toe 56 by a clamp-block 58 and screw 59 (Figs. 1, 9 and 12). Movable trimmer-blade 60 works in a 95 clearance beneath toe 55 and the movable member or section of the presser foot also located on the underside of said toe. Blade 60 is clamped to the lower end of the trimmer-arm 61, Fig. 1, which is the same in construction and operation as arm 643 of Fig. 47 of the aforesaid Merritt Patent 1,041,652, the construction being such that the upper movable blade 60 bears upon the upper surface of fixed blade 57 and, with its arm 61, participates in any upward movement of the presser foot and of blade 57.

The under surface of the presser foot which contacts the work is divided into three parts, sections or members. A shoe or bottom 65, removably secured to the underside of the toe-portion 56 of the foot-body, constitutes the work-contacting surface of a relatively fixed section or member of the foot (that is relatively fixed except for its movement as part of the entire foot) extending parallel to the direction of feed and along one side of the medial line of the seam. Said bottom 65 has two dowels 68 and 69. Dowel 68 projects through an opening in foot-body 30 with a washer 70 around its projecting end, and is engaged by a screw 71 the head of which bears against said washer, Fig. 9. Dowel 69 enters a recess in the underside of toe 56 and is engaged by a screw 72. As 110 thus apparent, bottom 65 is readily removable for replacement if worn, or for the substitution of another bottom of different thickness, such as the thicker bottom 65' shown in Fig. 11, when it becomes desirable 115 120 125 130

to change the elevation of cut by the trimmer blades.

- A shoe or bottom 75 constitutes the second and herein termed compensating section or member of the work-contacting part of the foot. Said shoe is yieldingly movable relative to the fixed section of the foot and lies parallel thereto on the other side of the medial line of the seam. A flaring notch 76 (Fig. 13) between the forward ends of the foot sections 65 and 75 is adapted to be entered by the upturned edges of the fabric in passing to the trimmer blades operating in said notch near the rear closed end thereof.
- 10 The mounting of compensating foot member 75 is as follows:—Two plungers 77, 77' work in vertical bearing openings in the main body portion 30 of the foot and in an extension 78 thereof which extends out over and is joined to toe 55 by a tubular post 79, and through which the bearing opening for plunger 77' extends. A screw 80 threaded into the upper end of each plunger has a head of larger diameter than its plunger adapted to contact an 15 annular shoulder about the interior of the bearing opening and act as a stop to limit the downward movement of the plunger by its spring. A spring 81 for each plunger, housed in the enlarged upper end of the 20 plunger opening, bears at its lower end against the head of screw 80 and at its upper end in a hollow screw plug 82 closing the upper end of the bearing opening.

As shown in Fig. 8, the compensating member 75 is lifted against the pressure of springs 81, 81, carrying the heads of screws 80, 80 somewhat above their coöperating stop shoulders. At its lower end, plunger 77 has a partly cylindrical cross-head 83. Plunger 40 77' has a similar cross-head 84. 83 and 84 are adapted to engage, with freedom of pivotal movement, undercut grooves 85, 86, respectively, in compensating foot-member 75. Screws 87 and 88, threaded into 83 and 84 45 respectively, have heads which overlap the edges of grooves 85 and 86 and hold the compensating foot-section 75 to its position relative to the other work-contacting sections of the foot. By reason of its pivotal connection to each of the plungers 77 and 77', and also by reason of the adaptability of said plungers to move inward and outward, the compensating member 75 of the foot may tilt or incline—for example, as when a piece of fabric is just entering beneath its forward end as shown in Fig. 18—and such tilting may be a simultaneous lowering at one end and rising at the other end.

The pressure exerted by main presser-foot 60 spring 34 is greater than that exerted by springs 81, 81, so that compensating foot-member 75 adapts its position to that taken by foot-member 65 and to the thickness of the fabric it engages. In other words, the 65 compensating foot-member 75 sustains what

may be termed a floating relationship to its companion foot-member 65. Spring 34 will always hold the relatively fixed foot-member 65 firmly in contact with the work thereunder. If there is greater thickness of work 70 or fabric under compensating foot-member 75, then its springs 81, 81 yield and permit its firm engagement with the work at an appropriately higher elevation than the bottom of foot-member 65, as shown, for example, in Fig. 17, where one thickness of fabric under foot-member 65 is to be joined to two thicknesses of fabric under compensating foot-member 75. With the conditions reversed, and the two thicknesses of fabric 80 under foot-member 65, the springs 81, 81 would press the compensating foot-member into contact with the lesser thickness of fabric leaving the member 65 at a higher elevation in engagement with the greater thickness of fabric. In thus automatically accommodating itself to differences and variations in thickness of material, the presser foot is enabled to maintain a firm and distributed pressure upon the work against the cloth-plate and feed-members, and to afford an even feed at both sides of the seam, regardless of differences and variations in the thickness of material.

When sewing upon work of the same 95 thickness at both edges of the seam, it is preferable to fix or lock the compensating member 75 with its work-contacting surface even with that of member 65, thus presenting the condition of the ordinary foot pressing upon the work at both edges of the seam under tension of the one spring 34. The preferred means for thus locking foot-member 75 are best shown in Figs. 8 and 10. A cylindrical bolt or locking member 110 is 100 mounted to slide horizontally in the enlargement 111 of the extension 78 of the body of the foot, the bearing opening at its opposite ends intersecting the vertical bearing openings for plungers 77 and 77'. Bolt 110 has 105 a head at one end and a tongue 112 at its other end adapted to make locking engagement with a notch 113 of plunger 77. Near its headed end, bolt 110 has a semi-circular recess 114 and adjacent thereto a tongue 115 110 adapted to make locking engagement with a notch 116 of plunger 77'. To lock the compensating foot-member, the presser foot is lowered into contact with the throat-plate. The pressure of spring 34 dominating that 115 of springs 81, 81, the two foot-members 65 and 75 are brought into even contact with the throat-plate, with foot-member 75 and its plungers in the position shown in Fig. 8. Bolt 110 is then pushed into its locking position, its tongues 112 and 115 engaging notches 113 and 116, respectively. To release foot-member 75, bolt 110 is pulled out, disengaging its tongues from the notches and bringing circular recess 114 into register 120 125 with the bearing opening of plunger 77. Bolt 110 is then pushed into its locking position, its tongues 112 and 115 engaging notches 113 and 116, respectively. To release foot-member 75, bolt 110 is pulled out, disengaging its tongues from the notches and bringing circular recess 114 into register 130

with the vertical opening in which plunger 77 works, so that plungers 77 and 77' and their foot-member 75 are free to move under the influence of their springs 81, 81. A 5 spring detent 117, secured by screw 118 (Figs. 2 and 16), co-operates with two notches 119, 119 (Fig. 10) in bolt 110 to hold the same against accidental displacement from either its locked or unlocked position, while 10 permitting the bolt to move under pressure.

In the modified form of locking means illustrated in Figs. 19 and 20, 120 is a locking plate slidable on two screws 121, 121, passing through slots 122, 122 of the plate 15 and threaded into the extension 78 of the foot-body 30. Plate 120 has two depending legs, one bowed outwardly to give clearance for other parts and each provided with a slot 123 in the lower end thereof. The 20 screws 87 and 88, before described, engage loosely through said slots respectively. An outwardly turned lug 124 affords a grip by which the plate may be moved either to its locking position with the narrow ends of 25 slots 122, 122 in engagement with the shanks of screws 121, 121, or to its release position with the large ends of said slots about said screws.

A chaining-foot 90, generally similar to 30 that of the patents aforesaid, constitutes the third work-contacting section or member of the presser foot. It is relatively larger than that of said patents and affords better control of the threads in chaining-off; it is 35 wider and is also extended forward to embrace needle opening 91, which, in the patents, is located in the body of the main foot in advance of the chaining-foot. An upturned flange 92 at the forward end of chaining- 40 foot 90 works close to an upright surface 93 and in front of a bar 94 (Figs. 3, 4 and 12), both of which are parts of the main body 30 of the foot. A notch 95 in the forward under edge of 90 forms a continuation of 45 notch 76 and merges into the flattened under surface of the chaining-foot in advance of the needle opening, whereby the trimmed edges are effectively flattened out and into abutment before arriving at the needles. 50 96 is a shank or stem, vertically movable in an opening 98 bored in the body of 30. A screw 97 threaded into stem 96, with its head movable in a slot (best shown in Fig. 1) in the wall of opening 98, limits the 55 movement of the chaining-foot relative to the main foot. A range of movement for the bottom surface of the chaining-foot, approximating one thirty-second of an inch above and below the bottom surface of the 60 foot-member 65, has been found to give satisfactory results. Spring 99, Fig. 12, yieldingly holds chaining-foot 90 to its work and tends to move it to its outward limit. Said chaining-foot is pivotally and 65 detachably connected to stem 96. A partly

cylindrical rib or fulcrum 100 is formed on foot 90 near its rear end, as by riveting a short rod thereto. A groove of greater than semi-circular cross-section across the lower end of stem 96, is adapted to receive rib 100 70 by sliding the latter endwise into the groove. When chaining-foot 90, thus attached to stem 96, is in its assembled position, it has freedom of vertical movement under the tension of spring 99 and also a range of 75 rocking movement on its fulcrum 100, being at the same time confined against sidewise displacement by the two foot-members 65 and 75 between which it is positioned. By removing stop-screw 97, chaining-foot 90 80 and its stem 96 may be withdrawn and then detached from each other. As shown in Fig. 18, fabric entering under the forward end of the foot-member 75 has not yet advanced as far as the needles while chaining- 85 foot member 90 is engaging a chain extending rearward from the line of the needles. As the thicker fabric enters under the forward end of chaining-foot 90, the latter will tilt upward at its forward end. 90

Reference has heretofore been made to the employment of substitute foot-bottoms 65, 65' to change the elevation of cut by the trimmer blades. With any such substitution, to preserve the most efficient relationship of parts it is desirable to employ correspondingly thicker or thinner substitutes for the compensating foot-member 75 and for chaining-foot member 65. Otherwise, for example, with the compensating foot-member 75 locked, its bottom surface would not stand even with the bottom surface of foot-members 65; and the range of movement of chaining-foot member might be too high or too low relatively to the other foot-members. 100

Figs. 13 and 14 illustrate the use of substitute foot-members 65 and 75 to provide different widths of notch 76 for thinner or thicker material. 110

130 is a guard or deflector for shielding certain of the stitch-forming elements, and more particularly for guiding to one side such trimmings as are removed by the trimmer blades. Said deflector is preferably a 115 strip of spring metal bent at one end to more than a semi-circle, forming clip 131 adapted to spring about and embrace the lower end of post 79. When so sprung in place, deflector 130 may be turned either to 120 its normal working position, shown in dotted lines Fig. 1, or to the position shown in Fig. 4, to give access to the parts which it normally shields, or it may be detached by pressure sufficient to disengage clip 131 125 from post 79.

Any suitable feed may be used in conjunction with the presser foot of this invention. Fig. 18 shows the use of a double feed—as in Merritt Patents 1,041,652 and 130

1,041,658—102 being a fulling feed-member and 103 a stitch feed-member working through an opening in the cloth-plate 104. As further illustrated in Fig. 17, the cloth-plate is carried by a work-arm 105, fragments of which are shown, and the stitch feed-member 103 has four sets of teeth working through four slots in the cloth-plate and co-operating with both members 10 65 and 75 of the foot.

Where the word "substitutive" is used in the claims with reference to bottom members 65 and 65' (Figs. 9, 10, 11, 13 and 14), it applies to any one of two or more such 15 parts each varying in its dimensions from the others. Likewise, where the word "substitutive" is used in the claims with reference to bottom member 75 (Figs. 8, 10, 13 and 14), it applies to any one of two or more of such 20 parts each varying in its dimensions from the others.

What is claimed is:—

1. A presser foot having a foot-body, two companion work-contacting surfaces on said 25 foot-body positioned to engage the work at opposite sides respectively of the medial line of the seam and forming between them a notch extending rearward from the forward end of the foot, and means movably mounting one of said surfaces on the foot-body under tension adapted to yieldingly hold it in engagement with work thereunder and enabling it to assume different elevations relative to the other surface and foot-body, said 30 mounting means also permitting rocking or tilting of said movable surface in the direction of the length of the seam.

2. A presser foot having a foot-body, two work-contacting surfaces or members on said 40 foot-body one fixed relative to the body, means movably mounting the other member on the foot-body, said mounting means including two upright plungers each pivotally connected to said movable member permitting 45 rocking or tilting of the latter in the direction of feed, and plunger-actuating springs for pressing said movable member into engagement with the work thereunder and enabling it to assume different elevations 50 relative to the other work-contacting surface.

3. In a presser foot, the combination with a foot-body, of a work-contacting member movably mounted on said foot-body acting to engage only one of two edges of fabric to be joined and adapted to operate either in movable or fixed relationship thereto, and means for locking the movable member to the foot-body when it is to operate in fixed relation thereto.

4. A presser foot having two work-contacting sections or members relatively movable for some conditions of operation and both positioned to engage the work in advance of the point of stitch formation, and

locking means for fixing said foot sections together for other conditions of operation.

5. A presser foot including a foot-body having a fixed and a relatively movable work-contacting member, both positioned to engage the work in advance of the point of 70 stitch formation, and locking means adapted to secure said movable member in fixed relationship to the foot-body for certain conditions of work.

6. A presser foot having a work-contacting section for engaging the work at one side only of the medial line of the seam, and another relatively movable and yielding work-contacting section adapted to engage the work at the other side only of said medial 80 line of the seam, and locking means adapted to secure the movable work-contacting section in fixed relationship to the other section for certain conditions of work.

7. A presser foot including a foot-body 85 having a fixed work-contacting member for engaging only one of two edges of fabric to be joined, a relatively movable work-contacting member for engaging only the other of said two edges of fabric, and locking means 90 adapted to secure said movable member in fixed relationship to the foot-body for certain conditions of work.

8. A presser foot having a foot-body, a work-contacting member in fixed relationship to the foot-body for engagement with the work at one side only of the seam, a second work-contacting member movably and yieldingly connected to said foot-body and thereby adapted to automatically accommodate itself to engagement with a different thickness of work at the other side only of the seam, and locking means for securing said movable work-contacting member in fixed relationship to the foot-body when both 100 work-contacting members are to operate upon work of the same thickness.

9. A presser foot having a foot-body, a work-contacting member positioned to engage work in advance of the point of stitch formation and movably mounted on said 110 foot-body with tension means for yieldingly pressing said member into engagement with work, and locking means for securing said movable member fixedly to the foot-body.

10. A presser foot having a foot-body, a work-contacting member positioned to engage work in advance of the point of stitch formation and movably mounted on said foot-body with tension means for yieldingly 120 pressing said member into engagement with work, and a sliding lock member for securing said movable work-contacting member in fixed relationship to the foot body.

11. A presser foot having a slot extending 125 rearward from its forward end, work-contacting members bordering opposite edges of said slot and one yieldingly movable with

relation to the other in its engagement with the work, and locking means for securing said movable member in fixed relationship to said other member.

5 12. A presser foot having a work-contacting member mounted to permit rocking thereof in the direction of the seam, and locking means for securing said member against such rocking movement for certain 10 conditions of work.

13. A presser foot having a work-contacting bottom member mounted to permit rocking thereof in the direction of the seam, and locking means for securing said member against such rocking movement for certain 15 conditions of work.

14. A presser foot having a slot extending rearward from its forward end, a work-contacting member bordering one edge of said 20 slot and engaging the work along one side only of the seam, a second work-contacting member bordering the other edge of said slot and movably mounted with tension means for yieldingly pressing it into engagement 25 with the work at the other side only of the seam, the mounting of said movable member also permitting rocking or tilting thereof in the direction of the length of the seam.

30 15. A presser foot having two approximately parallel work-contacting surfaces or members forming an intervening slot at their forward ends, one of said members being yieldingly movable relatively to the other for engagement with different thicknesses of 35 work, and one of said members being mounted to permit rocking or tilting thereof in the direction of the length of the seam.

16. A presser foot having a readily 40 removable substitutive work-contacting part the dimensions of which affect the functioning of the foot in its engagement with the work.

45 17. A presser foot having a readily removable substitutive work-contacting bottom member the dimensions of which affect the functioning of the foot in its engagement with the work.

18. A presser foot having a body part and 50 a readily removable substitutive work-contacting bottom member detachably secured to said body-part.

19. The combination with a presser foot, 55 of means operating in conjunction therewith in the formation of a seam, said foot having a readily removable substitutive work-contacting part the dimensions of which affect the operative position of said means.

20. The combination with a presser foot,

of means operating in conjunction therewith 60 in the formation of a seam, said foot having a work-contacting part the dimensions of which affect the operative position of said means, said part being readily removable for replacement by a substitute part of different 65 dimensions to alter the operative position of said means.

21. The combination with a presser-foot, of means operating in conjunction therewith 70 in the formation of a seam, said foot having a work-contacting bottom the dimensions of which affect the operative position of said means, said bottom being readily removable for replacement by a substitute part of different 75 dimensions to alter the operative position of said means.

22. The combination with a presser-foot, of trimmer mechanism operating in conjunction therewith, said foot having a work-contacting part the dimensions of which affect 80 the position of cut by the trimmer mechanism, said part being readily removable for replacement by a substitute part of different dimensions to alter the position of cut.

23. The combination with a presser foot, of trimmer-mechanism operating in conjunction therewith, said foot having a work-contacting bottom the thickness of which affects the elevation of cut by the trimmer-mechanism, said bottom being readily removable to permit the substitution of a bottom of different thickness to change the elevation 90 of cut.

24. A presser foot having as a part thereof a work-contacting member detachably secured in place and forming one edge of a slot in the foot, the detachability of said members adapting it to the substitution of another member shaped to give a slot of different dimensions.

100 25. A presser foot having as parts thereof two work-contacting members detachably secured in place to form between them a slot, the detachability of said members adapting them to the substitution of other members shaped to give a slot of different dimensions.

26. In a presser foot, the combination with a foot-body, of two work-contacting bottoms detachably secured to said body and forming an intervening notch extending rearward from their front ends, the detachability of said bottoms adapting them to replacement by other bottoms shaped to give a different width of intervening notch.

110 In testimony whereof I have signed this 115 specification.

ARTHUR A. MERRITT.
